SERRATED RULER

Barkere Boodakian, 5743 Lexington Ave.,
Los Angeles, Calif. 90038

Filed Sept. 16, 1970, Ser. No. 25,026

Term of patent 14 years

Int. Cl. D10—04

U.S. Cl. D52—6

FIG. 1

FIG. 2

FIG. 3

FIG. 1 is a front elevational view of serrated ruler showing my new design;

FIG. 2 is an opposite side elevational view thereof;

FIG. 3 is a right end elevational view thereof, the left end being identical thereto.

I claim:

The ornamental design for a serrated ruler, as shown, and described.
